UNITED STATES PATENT OFFICE.

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK.

DESIGN FOR A RING FOR CHANDELIERS.

Application filed November 23, 1928. Serial No. 29,019. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for a Ring for Chandeliers, of which the following is a specification, reference being had to the accompanying drawing, forming part thereof.

In said drawing:

Figure 1 is a bottom plan view of a ring for chandeliers embodying my new design. In this figure a segment of applied ornamen-

tation is shown while the outline of the ring is completed in dot and dash lines, it being understood that the pattern shown by the segment is repeated throughout the remaining area of the ring.

Figure 2 is a side elevation of the same, partly in full lines and partly in dot and dash lines.

I claim:

The ornamental design for a ring for chandeliers, substantially as shown and described.

CHARLES W. LOGAN.
